(57) **CLAIM**

The ornamental design for an interchangeable tool bit driver and holder, as shown and described.

DESCRIPTION

FIG. 1 is a perspective view of the new design for an interchangeable tool bit driver and holder, according to a first embodiment;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of the new design for an interchangeable tool bit driver and holder, according to a second embodiment;

FIG. 9 is a front view thereof;

FIG. 10 is a rear view thereof;

FIG. 11 is a left side view thereof;

FIG. 12 is a right side view thereof;

FIG. 13 is a top view thereof;

FIG. 14 is a bottom view thereof;

FIG. 15 is a perspective view of the new design for an interchangeable tool bit driver and holder, according to a third embodiment;

FIG. 16 is a front view thereof;

FIG. 17 is a rear view thereof;

FIG. 18 is a left side view thereof;

FIG. 19 is a right side view thereof;

FIG. 20 is a top view thereof; and,

FIG. 21 is a bottom view thereof.

The Design consists of the features of shape, pattern, configuration, and ornamentation of the interchangeable tool driver and holder shown in the drawings. Portions shown by dashed lines do not form part of the Design.
